By Ira J. Adams,
Attorney

UNITED STATES PATENT OFFICE.

HENRY JOSEPH ROUND, OF LONDON, ENGLAND, ASSIGNOR TO RADIO CORPORATION OF AMERICA, A CORPORATION OF DELAWARE.

THERMIONIC DEVICE.

1,361,099.

Specification of Letters Patent.

Patented Dec. 7, 1920.

Application filed May 21, 1920. Serial No. 383,281.

To all whom it may concern:

Be it known that I, HENRY JOSEPH ROUND, a subject of the King of Great Britain, and resident of 9 Woodberry Crescent, Muswell

5 Hill, London, England, have invented new and useful Improvements in Thermionic Devices, of which the following is a specification.

This invention relates to improvements in 10 thermionic transmitting devices or valves for wireless telegraphy and telephony.

The invention is illustrated by the accompanying drawing which is a section of a valve.

15 A is a hollow metal tube closed at its inner end and sealed at B into the glass of the bulb C and acting as the anode. It is surrounded by a grid D the lead from which passes out through the glass at E. F is a

20 filament which is arranged preferably as a coil around the grid and is maintained in position by supports G, the leads from it being sealed through the glass at H. I is a tube which is arranged along the axis of the

25 anode A and through which cooling fluid may be introduced. J is a cage or sheath of metal surrounding the filament for the purpose of preventing the emission from reach-

ing the glass. In some cases this sheath may be provided with a negative charge of electricity and the connection K may be used for this purpose.

In place of forming the filament as a single coil I may construct it in many other ways as the invention is not limited to specific constructions.

What I claim is:—

1. In a thermionic device, the combination of an anode, a grid surrounding the anode, a filament surrounding the grid and 40 a metal sheath surrounding the filament.

2. In a thermionic device, the combination of an anode, means for cooling it, a grid surrounding the anode, a filament surrounding the grid and a metal sheath surrounding the filament. 45

3. In a thermionic device, the combination of a hollow anode, means for leading cooling fluid thereto, a grid surrounding the anode, a filament surrounding the grid and 50 a metal sheath surrounding the filament.

In testimony that I claim the foregoing as my invention I have signed my name this third day of May 1920.

HENRY JOSEPH ROUND.
